(57) CLAIM

I claim the ornamental design for a handbag ornament, as shown and described.

DESCRIPTION

FIG. 1 is a perspective view of an handbag ornament showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a reduced scale perspective view of the handbag ornament illustrating my new design in the environment of a handbag.

Broken lines are used to illustrate environment and unclaimed portions of the handbag ornament.

Broken lines, and any boundary created thereby, form no part of the claimed design.
